ELECTRON DISCHARGE DEVICE UTILIZING
CAVITY RESONATORSLeon S. Nergaard, Princeton, N. J., assignor to
Radio Corporation of America, a corporation
of Delaware

Application March 27, 1944, Serial No. 528,195

7 Claims. (Cl. 315—6)

1

My invention relates to electron discharge devices and circuits therefor and particularly to such devices and circuits useful at ultra high frequencies.

The present application is directed to an improvement over the device and circuit shown in my co-pending application, Serial No. 514,206, filed December 14, 1943, and assigned to the same assignee as the present application.

Electron discharge devices using cavity resonators are used at ultra high frequencies. In the triode type, the electrodes are usually arranged in the order of cathode, grid and anode, and may have radially directed supports and lead-ins extending through the envelope and contacting the cavity resonator circuits. For example, in the triode an input cavity resonator, which may be of the coaxial line type, is connected between the cathode and grid, and the output resonator is connected between the grid and anode. In another type of tube referred to as an inductive output tube, the electrodes are in the order of cathode, grid, accelerator and collector. The input resonator, usually of the coaxial line type, is connected between the cathode and grid, a second resonator is connected between the grid and accelerator and the output resonator is positioned between the accelerator and collector. The resonator connected between the control grid and accelerator or screen is used to bring the accelerator to cathode potential for radio frequencies and is used for regeneration to compensate for the diode loading.

At ultra high frequency it is desired to so construct and arrange the leads to tube electrodes that they have as low inductance as possible, or, alternatively, to so arrange them that they comprise conductors of transmission lines which may be joined with an external circuit. Leads of triodes and of the triode section of inductive output tubes have been brought out in the same space sequence as the electrodes have within the tube, namely the sequence cathode, grid and anode, or in the case of the inductive output tube, the accelerator and collector. Because of this arrangement it is necessary to use the so-called grounded grid circuit, which is characterized by having a circuit between the grid and plate, or grid and accelerator. The disadvantages of this arrangement are, first, the full diode loading of the tube appears across the input circuit. This requires a higher driving power and results in a low power gain. Second, in the inductive output tube the circuit between the grid and accelerator is used to bring the

2

accelerator to cathode potential as far as radio frequency is concerned, or to introduce regeneration to compensate for the diode loading. Because regeneration tends to be unstable, tuning of the circuit is critical. It is desirable to eliminate diode loading and to remove the circuit between grid and accelerator. This would simplify tuning of the tube circuit without sacrificing performance.

10 It is, therefore, the principal object of my invention to provide an improved form of an electron discharge device and circuit useful at ultra high frequencies.

15 It is another object of my invention to provide such a device utilizing cavity resonators but in which the usual diode loading associated with tubes of this type is eliminated, and in which circuits requiring critical tuning are made unnecessary.

20 It is a further object of my invention to provide such a device utilizing cavity resonator circuits in which the grounded grid circuit is avoided.

25 The novel features which I believe to be characteristic of my invention are set forth with particularity in the appended claims, but the invention itself will best be understood by reference to the following description taken in connection with the accompanying drawing in which

30 Figure 1 shows a longitudinal section of an electron discharge device and circuit made according to my invention, Figure 2 is an enlarged detail section of the electrode arrangement of the device shown in Figure 1, Figure 3 is a transverse section taken along the line 3—3 of Figure 2 and Figure 4 is a diagram showing an equivalent circuit of the device shown in Figure 1.

35 In accordance with my invention I provide an electron discharge device having an elongated envelope 9 containing an indirectly heated cathode 10, control grid assembly comprising wires 11, collar 11', conductor 40, and cone-shaped collar member 41, accelerating electrode 12 and collector 13. The grid is supported by a ring conductor 14 sealed through the envelope and the cathode is provided with a ring seal contact 15 extending through the envelope and the accelerator is supported by a conducting ring

tubular member 21 is closed at one end by the conducting member 22 and provided at the other end with an end wall 24. The device is tuned by means of the tuning short circuit 23. This input circuit is coupled between the cathode and the grid, the grid being capacitively coupled to the inner member 20 insulated from the grid ring by means of the non-conducting collar 25, preferably of mica. The end wall 24 is provided with spring contact fingers 26 making direct electrical contact with the cathode.

The output circuit comprises a second resonator including disc end members 30 and 31 electrically connected at their peripheries by means of the collar 32. The end wall 31 is provided with collar 33 having spring fingers 34 electrically contacting the accelerator conducting ring 17; the other wall 30 is capacitively coupled to the input resonator through the mica insulating ring 35. Thus the accelerator and resonator may be maintained at a different voltage with respect to the input circuit. The input circuit may be maintained at ground potential since it is connected to the cathode.

In accordance with my invention I provide novel cathode and grid supports having cross-over connections which permit the cathode and input circuit to be maintained at ground potential. The grid includes grid wires 11 connected to the collar element 11' in turn electrically connected to and supported by the leads 40, these leads 40 being electrically connected to and secured to the cone-shaped grid collar member 41, in turn electrically connected to and supported by ring 14.

The cathode 10 is supported by leads 44, to heat insulate it, connected to collar 44'. The collar is supported by means of the rod and insulating bead construction 43, which securely and firmly supports the cathode within and coaxially of the grid. Radially directed wires or conductors 46 extend between leads 40 and electrically connect the cathode with the cathode ring 15. Thus an improved type of cross-over cathode and grid lead construction is provided which eliminates the objectionable features above mentioned of the usual electrode arrangement. A cathode heater lead 42 extends to the exterior of the envelope through which it is sealed. The other side of the heater is electrically connected to the cathode.

In Figure 4 is shown the equivalent circuit of the device shown in Figure 1, the numerals indicating the same elements as in Figure 1.

While I have indicated the preferred embodiments of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

What I claim as new is:

1. An electron discharge device having an envelope containing a cathode, a hollow grid assembly and another electrode, all in order named, said grid assembly including a collar member, said cathode being insulatingly supported solely from said grid assembly and enclosed entirely within said grid assembly, conducting means connected to said collar member, conducting means connected to said cathode and extending through said grid assembly but out of contact therewith,

and a cavity resonator coupled between both said conducting means.

2. An electron discharge device having an envelope containing a cathode assembly, a hollow grid assembly and another electrode in the order named, said grid assembly including a collar supporting means supported from said envelope, said cathode assembly being insulatingly supported entirely within said grid assembly and solely from said grid assembly, conducting means connected to said grid collar supporting means, conducting means connected to said cathode and extending through but out of contact with said grid assembly and a cavity resonator coupled between both of said conducting means.

3. An electron discharge device having a cathode, a hollow grid assembly and another electrode in the order named, said cathode being supported within said grid assembly and coaxially of said grid assembly by means of insulating spacer members, radially extending conducting means connected to said cathode and extending through but out of contact with said grid assembly, and a cavity resonator coupled between said grid assembly and said cathode conducting means.

4. An electron discharge device having a cathode, a hollow grid assembly and another electrode in the order named, said grid assembly including a conducting collar, a conducting cone-like member connected to one end of said collar, said cathode being mounted axially of said collar, and insulatingly supported within said grid and collar, radially extending conductors extending between said cone-like member and said collar and connected to said cathode, and a cavity resonator coupled between said grid and said cathode, one side of said cavity resonator being electrically connected to said radially extending conductors and the other side of said cavity resonator being capacitively coupled to said cone-like member.

5. An electron discharge device having an envelope containing a cathode, a hollow grid and another electrode in the order named, ring-like conducting members sealed through said envelope and spaced along said envelope, said grid including a collar having a flared skirt thereon and a foraminous portion supported thereon, said skirt being electrically connected to one of said ring-like conducting members, said cathode being insulatingly supported within said collar and grid, leads connected to said cathode and extending between said collar and said foraminous portion but out of contact therewith and electrically connected to another of said ring-like conducting members, and a cavity resonator coupled between said grid and cathode ring-like conducting members, one side of said cavity resonator being electrically connected to a ring-like conducting member and the other side of the cavity resonator being capacitively coupled to the other ring-like conducting member.

6. An electron discharge device having a cathode, a hollow grid and another electrode in the order named, ring-like conducting members spaced along the axis of said device, said grid including a collar having a flared skirt and a foraminous portion supported on said collar, said skirt being electrically connected to one of said ring-like conducting members, said cathode being insulatingly supported within said grid and collar, leads connected to said cathode and extending between said collar and said foraminous portion and collar but out of contact therewith

and electrically connected to another of said ring-like conducting members, and a cavity resonator coupled between said grid and cathode ring-like conducting members.

7. An electron discharge device having an envelope containing a cathode, a hollow grid and another electrode in the order named, ring-like conducting members sealed through said envelope and spaced along said envelope, said grid including a collar having a flared skirt and a foraminous portion supported at one end of said collar, said skirt being electrically connected to one of said ring-like conducting members, said foraminous portion being supported on said collar by a plurality of rod-like conductors spaced around said collar, said cathode being insulatingly supported within said grid, leads connected to said cathode extending between but out of contact with said rod-like conductors and electrically connected to another of said ring-like members,

and a cavity resonator coupled between said grid and cathode ring-like conducting members, one side of said cavity resonator being electrically connected to said cathode ring-like conducting member and the other side of the cavity resonator being capacitively coupled to said grid ring-like conducting member.
